UNITED STATES PATENT OFFICE.

FRANK E. SUMMERS, OF MEMPHIS, MISSOURI.

TRANSMITTER.

1,374,688.

Specification of Letters Patent. Patented Apr. 12, 1921.

Application filed May 12, 1919. Serial No. 296,530.

To all whom it may concern:

Be it known that FRANK E. SUMMERS, a citizen of the United States of America, residing at Memphis, in the county of Scott, 5 and State of Missouri, has invented new and useful Improvements in Transmitters, of which the following is a specification.

The purpose of the invention is to provide 10 a new and novel form of variable contact for use in transmitters and similar apparatus, whereby most effective variation of the resistance of the transmitter circuit may be had. The improved variable contact element is adapted for connection with other 15 and similar elements, so that a battery of such elements may be connected to and operated by a transmitter diaphragm.

The invention is illustrated and described 20 in a specific embodiment, to which, however, it is not to be restricted. The right is reserved to make such changes or alterations as the actual reduction to practice may suggest, in so far as such changes or alterations 25 are compatible in spirit with the annexed claims.

In the accompanying drawings:

Figure 1 is a view in side elevation of the 30 improved variable contact member showing the same attached to a transmitter diaphragm, a portion only of which is shown.

Fig. 2 is a section on the line 2—2 of Fig. 1.

Fig. 3 is a central vertical sectional view 35 through the variable contact member.

Fig. 4 is a section on the line 4—4 of Fig. 1.

Fig. 5 is a side elevational view showing 40 two variable contact members interconnected with the foremost in connection with a diaphragm.

Fig. 6 is a detailed sectional view in which there is shown a modified form of electrode for the variable contact member.

Referring to the drawings, the invention 45 is shown as comprising an inflexible disk 1 made of insulating material, this disk abutting the side of a cap 2 formed with an external thread to receive the clamping ring 50 3 which engages the outer periphery of the cap and holds the disk into firm contact therewith. The interior space comprised by the cap and the disk 1 provides a chamber in which a variable resistance material 55 4 may be carried. This variable resistance material is preferably carbon granules, but

any other material suitable to the purpose may be employed.

The cap 2 is made preferably of metal; likewise is the clamping ring 3. 60

The disk 1 is designed for attachment to a diaphragm such as that shown at 8 in the drawings, and to this end carries a threaded stud 5 formed with a head 6 lying against the inner face of the disk and carrying a 65 nut 7 bearing against the outer face of the disk, thus securing the stud firmly to the latter. The stud is also secured to the diaphragm 8, being passed through the latter and carrying the nuts 9 which abut the diaphragm on opposite faces and thus secure the diaphragm to the stud. Electrodes 10 are mounted in the disk 1 on diametrically opposite sides of the stud 5 and carry nuts 12 by means of which the conducting wires 75 13 may be secured to the electrodes.

The device just described comprises the 80 variable resistance element necessary for the effective operation of a transmitter and it is supported at the upper end of a flexible upright member 13 carried on an L-shaped bracket 14, this upright member 13 being secured to the cap 2 by means of a screw 15 which passes through the upright and engages in the threaded hole 16 of a plate 17, 85 the latter being attached to the cap 2 by suitable screws.

To oppose the pull of the diaphragm 8, a tension spring 18 is attached one end to the screw 15 and the other to a screw 19, the 90 latter being slidably mounted in the upright leg of the support 14 and rendered adjustable by a nut 20, the turning of which obviously serves to regulate the tension on the spring 18. 95

An upright 21 is mounted on the horizontal leg of the support 14 between the upright member 13 and the diaphragm 8, and this upright carries at its upper end an adjusting screw 22 and the vertical leg of the 100 bracket 14 carries an adjusting screw 23 aligned with the adjusting screw 22. Each of these screws has connected to it one end of a spring 24, the remaining ends of the springs being connected to the flexible upright 13. The obvious purpose of these springs and their adjusting screws is to so tension the flexible upright support 13 that the diaphragm 8 may move freely and readily respond to air vibration set up by the 110 voice.

In Fig. 5 there are shown two of these

variable resistance members connected in tandem, this manner of connection comprising the attaching of the stud 5 of one variable resistance member with the plate 16 of 5 the next.

In Fig. 6 there is shown a modified form 10 of electrode. This electrode is formed with a shank portion 25 passing through the disk 1 for the reception of a nut 12, the shank carrying a conical head 26 lying against the inner face of the disk 1 and having its conical surface in contact with the carbon granules 4.

In the operation of the invention the 15 vibration of the diaphragm 8 as a result of the sound waves set up by the voice causes the disk 1 and with it the cap 2 and the granules contained therein to vibrate, thereby varying the intensity of contact between 20 the granules and the electrodes. This disturbance set up in the carbon granules effects a variation of resistance in the transmitter circuit, since these granules are, by virtue of the electrodes 10 and the wires 13 25 included in the transmitter circuit as a part thereof.

While the disk 1 has been designed as an 30 inflexible disk, it is obvious that a flexible disk may be employed if desired. With a 35 flexible disk, it would probably not be necessary to have the flexible upright member as sensitive to the movement of the diaphragm 8 as is necessary when an inflexible disk is employed. The inflexible disk, however, is believed to be the preferable.

With reference to the construction shown 40 in Fig. 5, it is to be noted that the grouping of the transmitter resistance structures in tandem, makes for a more sensitive variation in the transmitter circuit, in that a variation is effected by each resistance element. Therefore the limits between which the variations in resistance may take place is increased.

45 The invention having been described, what is claimed as new and useful is:

1. In a transmitter, the combination of a diaphragm, an insulating disk having connection with the diaphragm, a cap attached

50 to the disk, a variable resistance substance carried within the cap, the cap having means 55 for attachment to a second disk, and electrodes carried by the said disk, whereby a plurality of caps and disks may be assembled in tandem with the diaphragm.

2. In a transmitter, the combination with 60 a diaphragm of an inflexible insulating disk, a stud connecting the disk with the diaphragm, a hollow cap against the open side of which the disk lies, a clamping ring 65 threadingly engaging the cap and bearing against the disk, a granular conducting material carried in the cap between it and the disk, electrodes mounted in the disk and in contact with the granular material, and a 70 resilient support for the cap for the useful purpose specified.

3. In a transmitter, the combination with 75 a diaphragm of an inflexible insulating disk, a stud connecting the disk with the diaphragm, a hollow cap against the open side of which the disk lies, a clamping ring 80 threadingly engaging the cap and bearing against the disk, a granular conducting material carried in the cap between it and the disk, electrodes mounted in the disk and in contact with the granular material, a resilient support for the cap, and adjustable 85 spring tensioning means for said support for the useful purpose specified.

4. In a transmitter, the combination with 90 a diaphragm, of an inflexible insulating disk, a rigid connection between the disk and the diaphragm, a hollow cap against the open side of which the disk is disposed, means detachably securing the disk to the cap, a granular conducting material carried in the cap and contacting with the disk, electrodes 95 mounted on the disk and in contact with the granular material, and supporting means for the cap and the disk and permitting the same to vibrate bodily with the diaphragm to effect variations in contact between the granular material and the electrodes.

In testimony whereof he affixes his signature.

FRANK E. SUMMERS.
